UNITED STATES PATENT OFFICE.

ARGYLE CAMPBELL, OF CHICAGO, ILLINOIS. ASSIGNOR TO ENTERPRISE RAILWAY EQUIPMENT COMPANY, OF CHICAGO, ILLINOIS, A CORPORATION OF ILLINOIS.

DUMP CAR.

Application filed January 30, 1922. Serial No. 532,733.

To all whom it may concern:

Be it known that I, ARGYLE CAMPBELL, a citizen of the United States, residing at Chicago, in the county of Cook and State 5 of Illinois, have invented a certain new and useful Improvement in Dump Cars, of which the following is a full, clear, concise, and exact description, reference being had to the accompanying drawings, forming a part 10 of this specification.

This invention relates to improvements in dump cars.

One object of the invention is to provide 15 in a dump car, efficient and relatively inexpensive means for locking the discharge doors in closed position.

A more specific object of the invention is the provision of a door locking arrangement having portions thereof utilized to 20 strengthen certain parts of the car construction which have heretofore been especially liable to injury.

In the drawings forming a part of this 25 specification, Figure 1 is a broken elevational view of a portion of a W-type hopper car showing my improvements in connection therewith. Figure 2 is a vertical, transverse, sectional view of the structure shown in Figure 1, taken at the left of the latter and 30 looking toward the right, only half of the car structure transversely being shown. Figures 3, 4 and 5 are enlarged detail sectional views corresponding to the lines 3—3, 4—4 and 5—5 respectively of Figure 1. Figure 6 is a side elevational view of a twin 35 door hopper car showing another embodiment of my improvements in connection therewith. And Figure 7 is a vertical transverse sectional view of the car shown in 40 Figure 6 and corresponding to the section line 7—7 thereof.

Referring first to the construction illustrated in Figures 1 to 5, inclusive, 10 denotes one of the side walls of the car, 11 45 a side stake, 12 one of the center sills, 13 the longitudinally extending ridge sheet over the center sills, 14 the transversely extending ridge sheet between the sets of hoppers, 15 one of the hopper bottom sheets sloped 50 downwardly from the end of the car toward the center, 16 an inner hopper side sheet, and 17 an outer hopper side sheet, the latter being sloped downwardly and inwardly toward the center line of the car. 55 As will be understood by those skilled in the

art, there are four hoppers similar to the one illustrated, two on each side of the center sill and arranged in pairs extending transversely of the car.

The hopper side sheets 16 and 17 are suitably flanged along their edges surrounding the discharge opening to provide the necessary strength as indicated at 16^a and 17^a respectively, and the lower edge of the bottom sheet 15 is reinforced by a transversely extending angle iron 18 secured on the under side thereof. Each hopper discharge opening is adapted to be closed by a sheet metal door as indicated at 19, the latter being hinged along their upper edges to swing 60 about axes extending transversely of the car. In the arrangement shown, each door 19 is hinged to a combined hinge butt and floor sheet stiffener 20, similar to that more specifically described and claimed in my co-pending application Serial No. 521,292 filed December 10, 1921, now Patent No. 1,437,091, granted November 28, 1922. Secured to each 65 transversely aligned pair of doors 19, adjacent the free edges thereof and parallel thereto, is an angle iron 21 provided with an enlarged or bulb edge 21^a. The bulb angle iron 21 is secured to both transversely aligned doors of a set so that the latter are 70 operated in unison. In the corner defined by the bulb iron 21 and the outer side edge of the door, is a pressed plate 22 riveted to the door proper and the iron 21 so as to provide additional strength. Where the outstanding flange of the bulb iron 21 passes 75 the flanged outer side edge of the door 19, said bulb angle iron is cut away as indicated at 21^b in Figure 1, it being understood that the bulb iron is extended an appreciable distance beyond the hopper side sheet 80 17 and the corresponding side edge of the door, to adapt it for cooperation with the latch, about to be described.

To hold the doors in closed position, I 85 employ a latch at each end of the bulb iron 100 21, only one of the same, however, being shown in the drawing. This improved latch, as shown, comprises, broadly, a bracket A; a latch lever proper B; and a locking cam C.

The bracket A, preferably in the form of a casting, has an inner main web 23 lying against the sloping side sheet 17 and secured thereto as by the rivets 24—24. Said web 23 is extended downwardly below the 105 110

bottom sheet 15 of the hopper, as shown at 23^a in Figure 3 and overlaps the corresponding end of the angle iron 18. The bracket casting A is also provided with a 5 transversely extending flange 25 parallel to and riveted to the outstanding flange of the angle iron 18. In addition, the bracket casting is formed with another flange 26 extending under, parallel to and riveted to 10 the hopper bottom sheet 15. With this arrangement, it will be noted that the bracket casting A secures the hopper side sheet 17, the hopper bottom sheet 15 and the bracing angle 18, at the lower corner 15 of the hopper, thereby preventing the hopper side sheet from tearing out or rusting out at this point, which has been a source of difficulty in cars of this type, heretofore.

20 The bracket casting A is provided also with an outer web 27 spaced from and parallel to the web 23, said web 27 being united to the web 23 by a flange 28 extending perpendicularly between the two webs 23 and 25 27, so that a housing is provided for the lever B and cam C. The flange 28 is reinforced at suitable intervals by ribs 29—29.

25 The latch lever B is pivotally attached to the bracket A by means of a pin 30 which 30 extends through suitable openings in the back wall or web 23 and the web 27. Said pin 30 has a headed inner end which seats within a recess 31 in the back web so that the pin 30 will be held in operative position 35 when the bracket A is secured to the hopper side sheet 17. The lever B swings in a plane parallel to the webs 23 and 27 and side sheet 17. Said lever is provided with a shank having one section 32 extending upwardly and 40 away from the pivot pin 30 and another section 33 which extends parallel to the hopper bottom sheet 15, when the lever B is in operative position. At its outer end, the lever B is formed with a shoulder 34 adapted to 45 engage and cooperate with the rounded bulb edge of the iron 21, said shoulder engaging the iron 21 at a point closely adjacent the side edge of the door and inwardly removed from the extreme outer end of said iron 21.

50 Said lever B is provided also with an outwardly and laterally extended shoulder 35 so disposed that a bar or lever may be inserted between it and the extended end of the bulb iron 21 so as to facilitate prying the 55 lever B upwardly to release the doors. The outer end of the lever B is rounded or beveled as indicated at 36 so as to act as a guide to lift the lever B when the doors are moved to closed position, said edges 36 being engaged by the bulb angle 21, as will be understood, the levers dropping into operative 60 position under gravity when the bulb iron has passed beyond the shoulders 34.

65 The locking cam C is pivotally supported 65 between the inner and outer webs of the

bracket A on a through rivet 37 which not only acts as a pivot for the locking cam C but also assists in securing the bracket A to hopper sheet. Said cam C is of well-known form and engages with a rounded edge 38 formed in the lever B on the upper side approximately where the the two sections 32 and 33 of the shank merge. 70

In the arrangement shown in Figures 6 and 7, transversely extending twin doors 40—40 are employed, pivoted to swing about transversely extending axes. The free edges of the pair of doors meet, and extending along the under side of each door near its free edge and parallel thereto, is a bracing beam 41 of substantially inverted U shape with the sides laterally flanged as indicated at 42—42. The sides of the hopper are sloped inwardly for a distance as indicated at 43 in Figure 7 and thence extended vertically downward as indicated at 44. Suitable reinforcing plates 45 are secured to the lower edges of the vertical portions 44. 80

85 To hold the doors in closed position, I employ the following arrangement. At each end of the brace 41 and within it is secured a forging or casting 46, the latter having an outwardly extending integral heavy pin or bar 47 of circular cross section. The pins or bars 47 are extended outwardly beyond the side edges of the door and also beyond the latching device, hereinafter described, so that the outer extended ends of said bars 47 may be used as handles in elevating the doors to closed position. 90

95 Cooperable with each of the extended pins 47 is a hook-shaped latch or lever 48 which is pivotally supported at its upper end by a bolt 49 which is housed within a bracket casting 50 secured to the vertical portion 44 of the hopper side sheet. Said lever 48 has a shoulder 51 adapted to engage under the rounded pin or bar 47 and hold the door, as will be obvious. The lower edge of the lever 48 is rounded as indicated at 52 so that, in lifting the door to closed position, the levers 48 will be cammed to one side until such time as the pins 47 have moved high enough to allow the shoulders of the latch levers to drop thereunder under the influence of gravity. Each lever also has an outwardly or laterally projecting pry-off lug 56. 105

110 Cooperable with each latch lever 48 is a locking cam 53 also pivotally supported from the housing bracket 50 by means of a bolt 54. The bolts 49 and 54 are extended through the side sheets so as to form part of the attaching means for the latch, there being additional rivets 55, as shown in Figure 6, to 115 secure the housing bracket. 120

I claim:

1. In a car provided with a hopper defined by side and bottom hopper sheets, the outer side hopper sheet forming a corner with the bottom sheet at the discharge open- 130

- ing, and a pivoted door to close said opening: the combination with a bracket having integral portions thereof secured to said bottom and side wall sheets at the intersecting corner; of a latch movably mounted on said bracket, said latch being adapted to cooperate with a member rigid with the door to lock the latter in closed position. 5
2. In a hopper dump car having a hopper defined by a sloping bottom wall and side walls, and a pivoted door to close the hopper opening, the combination with a member rigid with the door and projecting from one end thereof appreciably beyond the adjacent fixed side wall of the hopper; of a latch operatively supported from said side wall of the hopper and having a shoulder adapted to engage said projecting portion of said member between the end of the latter and the edge of the door, said latch being provided with a laterally extended shoulder with which a suitable operating tool is adapted to be used to effect disengagement of the latch. 10
3. In a dump car having a pivoted discharge door, the combination with a member rigidly secured to said door and having a rounded-off portion projecting appreciably beyond an edge of the door and beyond the adjacent fixed wall of the car; of a shouldered latch pivotally attached to said wall of the car and projecting across said edge of the door and adapted to engage and cooperate with said rounded-off projecting portion of said member at a point between the end of the latter and the edge of the door, said latch being provided with a laterally extended shoulder for use in disengaging the latch from said member. 15
4. In a car provided with a hopper having side and bottom walls meeting and forming a corner adjacent the discharge opening, and a pivoted door to close said opening: the combination with a member rigid with and projecting from the door; of a bracket having portions thereof secured to said bottom and side walls; and a latch pivoted to said bracket, said latch cooperating with said projecting member from the door. 20
5. In a car, the combination with a pivoted door having a projection from one of its edges; of means for locking said door in closed position comprising: a bracket secured to a fixed portion of the car, a latch engageable with said projection; a locking cam engageable with the latch; a headed pin for pivotally supporting the latch on the bracket, said pin extending through the bracket and having its head confined between the inner face of the bracket and the adjacent portion of the car, the aforesaid cam being pivotally supported on a pivot extending through the bracket and a fixed portion of the car. 25
6. In a car provided with a hopper having a downwardly sloping bottom wall and a side wall sloping from the vertical inwardly toward the center of the car, and a door for closing the discharge opening, said door being arranged to swing about an axis parallel to the plane of said bottom wall: the combination with a member rigidly secured to said door and projecting beyond one side edge thereof; of a bracket secured to said side wall and having a portion thereof extending under and secured to the bottom wall; and a latch pivotally mounted on said bracket to swing in a plane parallel to said inclined side wall, said latch having a shoulder adapted to engage and cooperate with said projecting member from the door. 30
7. In a hopper car having a pair of transversely aligned hopper doors: the combination with a bulb angle iron secured to said doors and rigidly uniting the latter, said bulb angle iron extending parallel and adjacent to the free edges of the doors; of pivoted shouldered latches mounted on fixed portions of the car, cooperable with the bulb edge of said angle iron to hold the doors in closed position. 35
8. In a car having a hopper defined by a bottom wall, inner and outer side walls, and a pivotally mounted door to close the discharge opening of the hopper: the combination with a reinforcing angle iron secured to the under side of the bottom wall along the lower edge thereof; of a bracket secured to one of the side walls of the hopper and extending over the end of said angle iron, said bracket having also portions extending under the bottom wall and secured to the latter and to the angle iron; a shouldered latch pivotally mounted on said bracket; and a member rigidly mounted on the door projecting therefrom with which said latch is adapted to cooperate in holding the door in closed position. 40
9. In a car, the combination with a pivoted dump door having a projection from one of its edges; of means for locking said door in closed position comprising: a bracket secured to a fixed part of the car and having inner and outer walls spaced from each other and connected by transverse walls; a latch engageable with the projection on the door, said latch being pivotally supported on the bracket by means of a headed pin extending through the inner and outer walls of the bracket, said pin having its head confined between the inner face of the bracket and the adjacent portion of the car; a locking cam engageable with said latch to hold it in operative position; and a pivot for pivotally retaining said locking cam, said pivot extending through the outer wall of the bracket and a fixed portion of the car. 45
10. In a dump car having a hopper defined by a sloping wall and side walls, and a pivoted door to close the hopper opening, the combination with a member on the door, 50

4
and projecting from one end thereof appreciably beyond the adjacent fixed side walls of the hopper; of a shouldered member supported from said side wall of the hopper and having a shoulder adapted to engage said projecting portion of said member between the end of the latter and the edge of the door, said shouldered member being provided with a laterally extended shoulder 10 with which a suitable operating tool is adapted to be used to effect disengagement of the member on the door from the shouldered member.

11. In a dump car, the combination with 15 a dump door; of a beam formed of a rolled section projecting beyond an edge of the door, said beam having the web thereof normal to the plane of the door and having outstanding marginal portions, one of said 20 marginal portions being secured to the door; and a shouldered latch mounted on a fixed portion of the car adapted to engage with

the other of said outstanding marginal portions of the beam.

12. In a dump car, the combination with 25 a dumping door having a flange at the edge thereof; of a beam member secured to the door and having a portion projecting beyond the plane of the flange, said beam having a web lying normal to the plane of the door and outstanding portions defining the margins of said beam, said beam being secured to the door by securing means passing through one of the said outstanding marginal portions; and a pivotally mounted shouldered door member adapted to engage with the other of said outstanding portions 30 to lock the door in closed position, said beam being formed with a cutaway portion to clear the flange of the door.

In witness that I claim the foregoing I have hereunto subscribed my name this 7th day of January, 1922.

ARGYLE CAMPBELL.
